BURGLARPROOF LOCK

Henry G. Voight, New Haven, Conn., assignor to
 Sargent & Company, New Haven, Conn., a corporation of Connecticut

Application May 13, 1939, Serial No. 273,376

2 Claims. (CL. 70—419)

This invention relates to locks, and more particularly to locks of the so-called pin tumbler type, which have provision for rendering the locks safe against unauthorized operation, such, for example, as being "picked" by someone with special tools which are provided for this purpose.

In picking a lock of the pin tumbler type, it is the practice to insert a slender tool into the key slot and raise the pins one by one until the break between the pins and the drivers registers with the upper surface of the key plug. When a pin is raised, the key plug is given a slight rotating torque so that when the pin is raised to the proper height the driver will stick in the extension or bore of the cylinder and thus remain in the position to permit the key plug to rotate. The pins are usually raised one by one to this position until finally the lock may be opened.

It is contemplated by the present invention to provide improved means to render impossible such unauthorized opening of the lock, and this result is accomplished by means of the fact that one of the sections of the tumblers is made in two parts, one of which consists of an open-ended cylinder and has a slight relative movement with respect to the other. This will permit a slight displacement of the key barrel under the force of a rotating torque when the break in the tumblers is not in registration with the junction of the key barrel and the bore in the cylinder. This slight displacement will prevent further raising of the pins, and will in this manner prevent unauthorized opening of the lock.

One object of my invention is to provide an improved lock of the pin tumbler type which will be relatively burglarproof.

A still further object of the invention is the provision of a lock of the pin tumbler type provided with tumblers consisting of pins and drivers, such that one of these elements will be made in two parts which overlap or telescope, but which are so made that one of these parts will be permitted lateral movement with respect to the other to prevent the picking of the lock and wherein one of the parts will be an open-ended cylinder having the driver spring acting directly thereon.

To these and other ends the invention consists in the novel features and combinations of parts to be hereinafter described and claimed.

50 In the accompanying drawing:

Fig. 1 is a longitudinal sectional view of a lock embodying my invention;

Fig. 2 is a transverse section on line 2—2 of Fig. 1;

Fig. 3 is a view similar to Fig. 2 but showing

the key plug rotated through a slight angle, as is done when an attempt is made to pick the lock;

Fig. 4 is a sectional view of one of the drivers.

To illustrate a preferred embodiment of my invention, I have shown a lock comprising the usual cylinder 10 having a bore within which is mounted the key barrel 11 designed to receive the operating key 12, the key being provided with notches 13 in the bit in order to align the tumblers in proper position for rotation of the key barrel, 10 as will be hereinafter explained. Secured to the rear end of the key barrel is the usual roll-back 14.

The cylinder 10 of the lock is provided with the usual pin tumbler extension 15, and this extension and the key plug 11 are provided with registering bores 16 and 17 to receive the tumblers. Such tumblers are normally made in two sections, one section being received in the key barrel, and the other being disposed principally in the bore 16 of the extension 15, the latter being forced downwardly against the lower sections by the springs 18. The lower of these two sections are termed pins and are shown at 19, while the upper sections of the tumblers upon which the springs 20 bear are termed drivers, and are shown at 20.

In the present lock one of these tumbler sections, in this case the pin 19, is made of the usual form and size, while the drivers 20 are, as will be hereinafter explained, specially designed to prevent the picking of the lock.

It will be seen that as the pins 19 are of the usual form and size, the tumbler mechanism will occupy no more space than is occupied in the ordinary pin tumbler lock which is not provided with any burglar-proof means. This is of considerable advantage in that the usual number of pins or tumblers may be employed with a cylinder of standard length, so that the provision of the burglar-proof structure does not limit the number of key changes that can be made, nor limit the adaptability of the lock to being master-keyed.

The second of the tumblers which is of special construction, in this instance the driver 20, is shown more especially in Fig. 4, and consists of two parts. The outer portion of this member is a cylindrical element 21 within which is received the other portion comprising a stem 22 and a head 23 secured to or integral with the stem. It will be noted that the outside diameter of the head 23 is substantially the same as the outside diameter of the cylinder 21, and that both head and cylinder fit relatively snugly in the bores 16 and 17, the head lying below and not entering 55

the cylindrical portion 21. The stem 22 is received within the member 21, but is of a size substantially smaller in diameter than the interior of the cylindrical member 21, so that the 5 stem 22 may be moved laterally with respect to and displaced from the center of the member 21, until the head 23 no longer registers with the exterior outline of the member 21.

It will be understood that in the usual form of 10 pin tumbler lock, when the proper key is inserted the pins are pushed upwardly until the break between the pins and the drivers is aligned or brought into registration with the upper surface of the key plug, or the "break" between the key 15 plug and the cylinder. The key plug is then free to be turned by the key in the usual manner. In the present lock the proper key raises the pins 19 until the break between these pins and the member 23 is in the proper position, and the key 20 plug may then be rotated by the key in the normal manner. In other words, this break between the pins 19 and the heads 23 corresponds to the break between the pins and drivers in the ordinary lock, so that the normal operation of the 25 present lock is exactly the same as one which is not provided with burglar-proof construction.

When, however, it is attempted to pick the lock by use of the ordinary instrument which raises one of the pins 19 until the key plug may be 30 slightly moved under a rotating torque, this rotating torque will effect such slight movement of the key plug when the upper surface of the head 23 arrives at the junction of the key plug and cylinder bore, as shown in Fig. 3. The key plug 35 is then slightly displaced, this displacement being permitted by the lateral movement of the stem in the cylindrical element 21. The head 23 on the stem 22 is moved slightly to one side until it is no longer in registration with the bore 16 in the pin tumbler extension, as shown in Fig. 40 3. Further upward movement of the driver is, therefore, prevented, although the key plug will be securely held against further rotation by means of the stem 22. Moreover, the person 45 tampering with the lock receives the indication that the pin has been raised to the proper point to permit opening of the lock, and while holding this pin at this point, proceeds to work upon the following pin. When they have all been brought 50 to this point, it would be expected that the lock

would open, but the key plug is being held against rotation by all of the stems 22, and the burglar, finding that the key plug will not rotate, must begin his operations over again, as he does not know which one of the pins is acting, or whether all of them are acting, to prevent rotation of the plug. 5

While I have shown and described a preferred embodiment of my invention, it will be understood that it is not to be limited to all of the details shown, but is capable of modification and variation within the spirit of the invention and within the scope of the appended claims. 10

What I claim is:

1. A pin tumbler lock having a tumbler extension and a key plug, said members having registering bores, cooperating tumbler elements mounted in said bores comprising pins generally contained in the bores of the key plug and drivers generally contained in the bores of the tumbler extension, each of said drivers comprising a pair of elements, one of said elements consisting of a headed stem, said head fitting snugly in the bore and said stem being of reduced size, and the other element of the driver comprising a hollow cylindrical member open at both ends, said member loosely surrounding said stem and fitting snugly within the bore of the tumbler extension, and a coil spring in said bore resting against the upper edge of said cylindrical member out of contact with said stem. 15 20 25

2. A pin tumbler lock having a tumbler extension and a key plug, said members having registering bores, cooperating tumbler elements mounted in said bores comprising pins generally contained in the bores of the key plug and drivers generally contained in the bores of the tumbler extension, each of said drivers comprising a pair of elements, one of said elements consisting of a headed stem, said head fitting snugly in the bore and said stem being of reduced size, and the other element of the driver comprising a hollow cylindrical member open at both ends, said member loosely surrounding said stem and fitting snugly within the bore of the tumbler extension, and a coil spring in said bore resting against the upper edge of said cylindrical member out of contact with said stem, and said pins in the key 30 35 40 45 50 plug being of standard size and construction.
